(57) **CLAIM**

The ornamental design for a hard disk drive case, as shown and described.

DESCRIPTION

FIG. 1 is a perspective view of a hard disk drive case showing our new design.

FIG. 2 is a top plan view thereof.

FIG. 3 is a bottom plan view thereof.

FIG. 4 is a side elevational view thereof.

FIG. 5 is a front elevational view thereof, including an indication of an area to be depicted in closer view in FIG. 7; and, FIG. 6 is a rear elevational view thereof.

The broken lines shown are for the purpose of illustrating unclaimed portions of the hard disk drive case and form no part of the claimed design.
